REFRIGERATING APPARATUS

Rolf M. Smith, Dayton, Ohio, assignor to General Motors Corporation, Dayton, Ohio, a corporation of Delaware

Application September 29, 1939, Serial No. 297,148

8 Claims. (CL 230—232)

This invention relates to refrigerating apparatus and particularly to a motor-compressor unit for refrigerating systems.

An object of my invention is to provide an improved sealed motor-compressor unit for use in refrigerating systems.

Another object of my invention is to provide a sealed motor-compressor unit of the type wherein a structure which carries the operating parts thereof is resiliently supported in an improved manner within a sealed casing so as to minimize noises and eliminate damage to the structure during shipping of the unit.

Another object of my invention is to provide a sealed motor-compressor unit of the type wherein a casing providing the sealing enclosure for operating parts of the unit forms a part of the low pressure side of a refrigerating system and wherein refrigerant entering the compressor and refrigerant discharged therefrom is muffled in an effective manner to reduce noises to a minimum.

A further object of my invention is to provide a sealed motor-compressor unit of the type wherein a casing providing the sealing enclosure therefor forms a part of the low pressure side of a refrigerating system and wherein a body of lubricant in the lower part of the sealed enclosure is heated by refrigerant discharged from the compressor for evaporating refrigerant therefrom to insure the maintenance of a body of substantially undiluted oil within the casing for circulation to operating parts of the unit.

A still further object of my invention is to provide an improved pipe connection from a resiliently mounted compressor within a sealed motor-compressor unit to the exterior of the unit which is resilient to permit a certain amount of movement of the unit relative to its enclosing casing without danger of breaking the rigid connections of the pipe and the movement of which pipe is muffed to eliminate noises during vibrations thereof.

In carrying out the foregoing objects it is a still further and more specific object of my invention to provide an improved structure for and method of separating refrigerant from oil in a sealed motor-compressor unit and to insure the circulation of oil substantially free of refrigerant to operating parts of the unit.

Further objects and advantages reside in the cooperation of parts of the structure which facilitates the manufacture and assembly of my improved motor-compressor unit and in novel combinations and arrangements to provide an

efficient, quiet operating and durable unit, as will more fully appear in the course of the following description.

In the drawings:

5 Fig. 1 is a horizontal section through the machine compartment of a refrigerator cabinet showing a top plan view of a refrigerant translating device including a motor-compressor unit;

10 Fig. 2 is a vertical section through the machine compartment of a refrigerator cabinet showing a side view of the device disclosed in Fig. 1;

15 Fig. 3 is a transverse vertical sectional view of a sealed motor-compressor unit included in the device shown in Figs. 1 and 2 and constructed in accordance with my invention;

20 Fig. 4 is a horizontal section taken on the line 4—4 of Fig. 3 in a direction upwardly of the bottom of the motor-compressor unit;

25 Fig. 5 is a horizontal section of the motor-compressor unit taken on the line 5—5 of Fig. 3 and showing the cylinder and piston portion of the compressor;

30 Fig. 6 is a fragmentary horizontal section taken on the line 6—6 of Fig. 3 showing the refrigerant inlet conduit and chamber construction of the compressor;

35 Fig. 7 is a vertical sectional view through the head of the compressor and is taken on the line 7—7 of Fig. 3;

40 Fig. 8 is a sectional view taken on the line 8—8 of Fig. 3 showing the refrigerant inlet valve of the compressor; and

45 Fig. 9 is a vertical sectional view taken on the line 9—9 of Fig. 3 showing the relation of the oil separator with respect to the discharge refrigerant muffler of the unit.

50 Referring to the drawings, for illustrating my invention, I have shown in Figs. 1 and 2 a refrigerating apparatus including a cabinet of the usual household type having a machine compartment 10 in the lower portion thereof and a plurality of insulated walls 11 forming or surrounding a food storage compartment (not shown) above the machine compartment 10. The horizontal frame members 12 of the cabinet have spaced apart metal cross members 14 secured thereto and upon which a refrigerant liquefying and condensing apparatus is supported. The refrigerant liquefying and condensing apparatus 55 comprises a motor-compressor unit generally represented by the reference character 15 and a conventional condenser 16 supported from the unit 15 in any suitable manner such as by the brackets 17. Unit 15 is provided with a plurality of outwardly extending legs 18 which are bolted,

preferably by resilient rubber mounting devices, to the metal cross members 14 for supporting the refrigerant liquefying and condensing apparatus within the machine compartment 10 of the refrigerator cabinet. The unit 15 has a pipe 19 extending therefrom and leading to the condenser 16 for conveying compressed refrigerant from the motor-compressor unit to the condenser. Compressed refrigerant discharged from unit 15 is cooled and liquefied in the condenser 16 and flows through a pipe 21 to a liquid refrigerant receiver 22. Liquid refrigerant flows from the receiver 22 through a pipe 23 upwardly to an evaporator (not shown) usually located in intimate heat exchange relation with the interior of the food storage compartment of the refrigerator cabinet. The evaporator upon absorbing heat from the food compartment causes liquid refrigerant in the evaporator to vaporize and this gaseous refrigerant is returned to the motor-compressor unit 15 through the pipe 24. The temperature of the evaporator or of the interior of the food compartment, formed by the insulated walls 11, is ordinarily controlled by a thermostatically operated switch (not shown) having an electrical connection 26 with a terminal box 27 provided with lead wires 28 entering the unit 15 by way of terminals 29 and connected with the motor thereof for governing operations of unit 15.

Since my invention is particularly directed to an improved sealed motor-compressor unit employed in closed refrigerating systems of the type illustrated, reference to Fig. 3 of the drawings is made in order to describe the construction thereof. The unit 15 includes a main spider-like frame 31 provided with a central vertical bore forming a bearing 32 for a shaft 33 disposed therein. Spider-like frame 31 is also provided with a plurality of upstanding wall portions 34 concentric with the shaft bore (see Figs. 3 and 4), and which wall portions have outwardly directed arms 35. The top surface of the bottom portion of main frame 31 is provided with a raised bead 36 which forms a valley 37 around the lower part of shaft bearing portion 32 for a purpose to be hereinafter described. The bottom of frame 31 has a plane surface 38 formed thereon and disposed perpendicularly to the shaft bore. Wall portions 34 receive and support a motor stator generally represented by the reference character 41 and having windings connected by leads 42 through the terminals 29 to wires 28. A motor rotor, generally represented by the reference character 43 and located within the motor stator, is rigidly secured to a metal member 44 such as by being tightly pressed thereon. The member 44 has a central bore which receives the upper end of shaft 33 and is preferably rigidly secured to the shaft by being tightly pressed thereon. Rotation of motor rotor 43, therefore, rotates member 44 and shaft 33 due to the rigid connection of member 44 with rotor 43 and shaft 33. Member 44 is hollowed out to fit over and surround the upper portion of shaft bearing 32, and a thrust washer 45 is disposed between the top end of bearing 32 and the inner surface of the hollowed out part of member 44. Washer 45 is provided with a groove or a plurality of grooves 46 for a purpose to be hereinafter described. Shaft 33 has an enlarged integral lower portion 48 provided with an integral shaft extension 49 which has its vertical axis offset horizontally relative to the vertical axis of shaft 33 so as to be rotated around the vertical axis of

the shaft bore. The offset shaft extension 49 is adapted to operate parts of the compressor portion of unit 15, and this compressor portion includes a housing 51 having a horizontally disposed cylinder 52 formed therein. Housing 51 has a plane top surface that is secured in sealing engagement to the plane bottom surface 38 of main frame 31 by bolts or the like 53 (see Figs. 4 and 6). A piston 54 located within cylinder 52 is welded or otherwise suitably secured to a horizontally disposed collar-like element 55 provided with aligned elongated openings for receiving the shaft extension 49. A horizontally disposed slider 56 fits within collar 55 and is provided with a vertical opening which receives the shaft extension 49 and with cylindrical outer wall surfaces forming a bearing for collar 55 (see Figs. 3 and 5). The construction and arrangement of the elements of the connection between the offset shaft extension 49 and piston 54 form what is commonly termed a "Scotch yoke" connection. The Scotch yoke connection is held in place relative to the shaft extension 49 by virtue of the piston fitting within cylinder 52 formed in housing 51.

A sheet metal member 58 is located at the outer end of housing 51 and a valve plate 59 and a compressor head 61 are disposed respectively over member 58. Member 58, plate 59 and head 61 are clamped in place upon the outer end of housing 51 by bolts or the like 62. Sheet metal member 58 is provided with an opening which registers with an opening 63 provided in valve plate 59. Member 58 is also provided with a pair of openings 64 (see Fig. 8) which register with a like pair of openings 65 (see Fig. 3) provided in the valve plate 59. The sheet metal member 58 is cut out as at 66 (see Fig. 8) to form a valve 67 which covers an inlet port 68 provided in valve plate 59. Compressor head 61 is hollowed out as at 71 to provide communication between the holes 63 and 68 in the valve plate. Head 61 is also hollowed out as at 72 to provide a discharge passage for refrigerant compressed by the compressor piston 54. A reed valve 73 located within the hollowed out part 72 of compressor head 61 (see Fig. 7) and secured by screws 74 to valve plate 59 covers the discharge opening 65 in plate 59 and is pressed against plate 59 by a spring 75 which surrounds a stud 76 staked or otherwise rigidly secured to the head 61. A central web 78 (see Fig. 7) provided on the head 61 partitions the inlet and outlet passages leading to and from the compressor cylinder. The chamber or hollowed out part 72 of head 61 is provided with an opening 79 in which an end of a pipe 81 is disposed and secured for conveying refrigerant compressed by the compressor therefrom. The upper part of housing 51 is hollowed out as at 83 and 84 (see Fig. 6) to provide two chambers which are separated by a web 85 having a hole 86 therethrough providing communication between the chambers. The outer wall 87 of chamber 84 has a hole 88 therein which is in alignment with the hole provided in member 58 and registering with the hole 63 in valve plate 59 (see Figs. 3 and 6). A pair of bores 89 extending through housing 51 to chamber 83 each have one end of a pair of pipes 91 secured therein, which pipes are bent upwardly and have their opposite end terminating in the vicinity of the top edge of the upstanding wall portions 34 of main frame 31.

Pipe 81 extends from the compressor head 61 to a sheet metal muffler device generally repre-

sented by the reference character 92 and secured to the bottom of housing 51 by screws 93 (see Figs. 3 and 4). This muffler device comprises a top plate 94 provided with a central opening 96, the edge of which is flanged upwardly as at 97 and also provided with two embossed or raised portions 98 and 99. Device 92 also comprises a lower sheet metal member 101 (see Fig. 9), shaped to form a doughnut-like chamber 102, and an intermediate plate 103 which is cut out as at 104 (see Fig. 4) to provide a plurality of integral depending legs 105. The legs 105 of plate 103 partition the chamber 102 into a plurality of compartments and these legs are cut off as at 106 to provide communication between the plurality of compartments within chamber 102. One leg 105a, of the plurality of legs 105 located intermediate the embossed portions 98 and 99, is devoid of the cut off portion 106 (see Fig. 9) and forms a closed partition in the chamber 102 between the embossed portions 98 and 99 so as to cause refrigerant to flow entirely around the chamber 102. The sheet metal member 101, top plate 94 and intermediate plate 103 are all welded or otherwise suitably secured together to provide a unitary device. The lower member 101 and intermediate plate 103 of device 92 are provided with a central opening which registers with the opening 96 in the top plate 94. A metal screen 108 in the form of a disc has its edge welded or otherwise suitably secured to the lowermost point of the bottom sheet metal member 101. The muffler device 92 is mounted on housing 51 so that the center of openings in member 101 and plate 103 and the center of opening 96 in plate 94 are in vertical alignment with the axis of shaft 33 located in the shaft bore of main frame 31. A hollow inverted cone-shaped element 111 having a cover 112 is secured to the eccentric or offset extension 49 of shaft 33 by a screw 113.

Heat generated by the compressor is transmitted through piston 54, collar 55, slider 56 and shaft extension 49 to the element 111 to thereby maintain this element at a higher temperature than the body of liquid in the unit for a purpose to be hereinafter described. Cover 112 of element 111 is provided with holes 114 and 115 for a purpose to also be hereinafter described. The axis of cone-shaped element 111 is disposed in the vertical plane of the shaft 33, and rotation of the shaft extension 49 around the axis of shaft 33 causes rotation of element 111 about the same axis of shaft 33. A pipe 116 having its one end secured to the embossed portion 98 in plate 94 of device 92 has its other end secured to a connector 117 sealed to and extending through a wall of a lower casing 118 of the unit. The pipe 116 communicates with the pipe 19 through the connector 117 and the portion of pipe 116 intermediate its ends is rendered resilient by being formed into a coil 119 having a turn or turns surrounding the compressor of the unit. In order to prevent coil 119 formed by pipe 116 from generating or creating noises, due to the resilient mounting of the unit within its sealed casing, as will be presently described, I provide a snubber element 121 in the form of a strip of spring metal which is vertically disposed against the compressor head 61. The element 121 has inturned portions 122 punched therefrom which engage the upright side walls of the compressor head 61 and has its ends cut out to provide a U-shaped slot therein, the walls of which slots are bent in a horizontal direction to provide legs 123

which straddle a convolution of the pipe coil 119. The abutment of element 121 with compressor head 61, engagement of portions 122 thereof with side walls of head 61 together with the legs 123 straddling and engaging the pipe coil 119 holds the element 121 in place within the unit and causes same to snub or reduce vibrations of the coil 119 to thereby prevent same from creating noises during operation of the unit. Lower casing 118 of unit 15 is provided with a connector 125 which extends through a wall thereof and has the refrigerant pipe 24 secured thereto. This connector 125 has a short pipe 126 secured to its inner end and which pipe 126 is bent so as to extend upwardly to a point above the mounting legs 35 of main frame 31 within the unit.

A dome 130 is welded to the lower casing 118, and this dome and casing provide a sealed enclosure for the motor-compressor unit 15. The parts of the motor-compressor are supported from dome 130 by a plurality of resilient mounting devices. Each of these mounting devices includes a metal bracket 131 welded to the inner upright wall surface of dome 130 and having an upper horizontal leg 132 and a lower horizontal leg 133. The lower leg 133 of bracket 131 is provided with a slot for the reception of a stud 134 which has a threaded shank 135 extending through the slot in leg 133 and which shank has a nut 136 thereon. A clip 137 is disposed between nut 136 and the bottom surface of leg 133 of bracket 131, and this clip fits around a shuddled portion of the leg 133 and has a part thereof bent over so as to engage the nut and lock same in position. The upper portion of stud 134 has a spiral groove cut therein for threadably receiving the lower end portion of a coil spring 138. A stud 139 has a portion 141 threaded into the arm 35 of main frame 31 and is provided with an integral depending portion 142. The stud 139 also has a spiral groove cut therein for receiving the upper end portion of spring 138. Thus, spring 138 is locked between the main frame 31 and brackets 131 to resiliently support the motor-compressor within the sealed unit 15. A small spring 144 has its convolutions coiled around the wire forming at least one convolution of the compression or supporting spring 138 and its function is to prevent spring 138 from generating noise during vibration thereof when the motor-compressor unit operates. The resilient mounting devices are novel in that the upper legs 132 of brackets 131 are in the path of upward movement of arms 35 of main frame 31 and these legs 132, therefore, prevent movement of the motor-compressor unit upwardly beyond the resiliency of pipe coil 119 to eliminate danger of breaking the refrigerant pipe 116 at its rigidly connected ends. The depending portions 142 of studs 138 are shaped to engage the inner portions of the convolutions of springs 138 when the motor-compressor unit moves sideways relative to the enclosing dome 130 to thereby snub or cushion horizontal movement of the motor-compressor. The relation of legs 132 of brackets 131 relative to the upper surface of arms 35 and relative to the upright wall portions 34 of main frame 31 prevents damaging the refrigerant pipe connections within the sealed unit during shipping thereof by virtue of forming a stop for upward and sidewise movement of the motor-compressor.

The interior of the unit 15 forms a part of the low pressure portion of the refrigerating

system and is, therefore, under compressor suction pressure. A body of lubricant, preferably heavier than the refrigerant employed in the system, is contained in the bottom of the sealed enclosure. Lubricant from the body of liquid in the unit is raised by the element 111 in a manner to be hereinafter described and is caused to flow through a hole 146 drilled through the shaft extension 49 and terminating in communication with the lowermost portion of a spiral groove 147 cut in the surface of shaft 33. Shaft extension 49 is provided with a horizontal hole 148 extending from hole 146 to a groove provided around the extension and which groove communicates with horizontally disposed holes 149, provided in slider 56. A hole 151 provided in the shaft bearing portion 32 of frame 31 permits oil to flow from the shaft bearing surface into the valley 37 and into a cavity 152 provided in frame 31 and through a hole 153 cut in the bottom wall of frame 31. The opening 153 registers with a passage 154 provided in housing 51, and this passage 154 directs the oil onto the compressor piston to lubricate the compressor cylinder.

When the electric circuit to the motor stator is completed, in response to a demand for refrigeration within the food compartment of the refrigerator, the stator 41 causes rotation of the motor rotor 43. Rotation of rotor 43 rotates member 44 and shaft 33 to cause rotation of the eccentric shaft extension 49 in a circle around the axis of the shaft 33. This rotation of shaft extension 49 causes reciprocation of slider 56 within the collar-like element 55 during movement of element 55 to and from housing 51 to reciprocate the piston 54 within the cylinder 52. Refrigerant evaporated in the evaporator of the refrigerating system is conveyed through pipe 24, connector 125 and pipe 126 into the interior of the sealed unit. When the piston 54 moves in a direction outwardly of its cylinder 52 during reciprocation thereof, the valve 67 is moved away from the port 68 and gaseous refrigerant contained in the sealed unit 15 is drawn through the pipes 91, passages 89, chamber 83, hole 86, chamber 84, holes 88 and 63, chamber 71 and hole 68 into the cylinder 52. Drawing the gaseous refrigerant through the series of passages and chambers in the structure disclosed reduces suction noises to a minimum without materially interfering with the flow of gaseous refrigerant to the cylinder and without loss of efficiency. Upon the return stroke of piston 54, during its reciprocation, valve 67 is caused to close or seal the port 68 whereupon the gaseous refrigerant is compressed in the cylinder 52 and this compressed refrigerant in openings 64 in member 58 and holes 65 in plate 59 causes valve 73 to be lifted from its seat and permit the compressed refrigerant to flow into the chamber 72 and into the pipe 81. The compressed refrigerant is directed by pipe 81 into the device 92 on one side of the closed partition 105a within the doughnut-shaped chamber 102 thereof. The compressed refrigerant flows from one compartment to another within chamber 102 and beneath the partitions 105 to the outlet chamber on the opposite side of the one partition 105a. Any oil circulated with the compressed refrigerant settles to the bottom of the doughnut-shaped chamber 102 and is forced from one compartment to another of the chamber by refrigerant flowing through the small passages provided by the cut-off parts 106 of legs or partitions 105 to the outlet chamber. By caus-

ing the compressed refrigerant to pass through the plurality of compartments within device 92, noises created by refrigerant being discharged from the compressor are deadened or eliminated. The compressed refrigerant and oil circulated therewith through device 92 enters the pipe 116, communicating with the outlet thereof, and is directed through the pipe coil 119 and connector 117 to the exterior of unit 15. Pipe 19 secured to connector 117 conveys the compressed refrigerant into the condenser 16 where it is cooled and liquefied prior to being circulated to the evaporator of the refrigerating system. Oil returned to unit 15 along with evaporated refrigerant settles to the bottom of the interior of the unit and accumulates therein in the form of a body of liquid. The oil inherently contains some refrigerant, and the body of liquid in the bottom of the unit is, therefore, somewhat turbulent. The shape of device 92 together with the screen 108 provides a quiet zone at the center of the interior of unit 15; and it is, of course, desirable to remove lubricant from the body thereof at this quiet zone. Since the bottom of cone-shaped element 111 is open and normally projects into the body of liquid in unit 15, rotation of element 111, about the vertical axis of rotation of shaft 33, by rotation of the shaft extension 49 around the axis of the shaft causes same to elevate liquid from the body thereof. This elevated liquid may be a mixture of refrigerant and oil and because of the higher temperature of element 111 the refrigerant passes into a gaseous state. Then due to the speed of rotation of element 111, the oil, which is heavier than the refrigerant gas, flows upwardly within the cone-shaped element while the refrigerant separates and flows outwardly of the element through the aperture or opening 114 in the center of the top wall thereof. Thus, substantially pure oil or oil devoid of refrigerant clings to the wall of element 111 and is whirled to the top of the tapered wall thereof where it flows outwardly of element 111 through the off-center aperture 115 in its top wall 112. Since aperture 115 communicates with the hole 146 in shaft extension 49, the relatively pure oil is forced upwardly in hole 146 to the horizontal hole 148 in shaft extension 49 and to the spiral groove formed around shaft 33. Rotation of shaft extension 49 causes hole 148 therein to continuously communicate with the opposed holes 148 in slider 56 whereby oil is fed to the bearing surfaces of the shaft extension 49 with slider 56 and to the bearing surfaces of slider 56 with the collar-like element 55. Oil forced upwardly within hole 146 beyond the moving parts of the Scotch yoke is fed into the spiral groove 147 around shaft 33 and this oil lubricates the shaft bearing in the main frame 31. Some oil conveyed upwardly within the shaft bearing, by the spiral groove 147, leaves the bearing surface through opening 151 and flows downwardly to the valley 37 formed in the upper face of the bottom wall of main frame 31. A quantity of oil is conveyed by the groove 147 to the top of the shaft bearing and lubricates the bearing surface of thrust washer 45, and its exit therefrom is effected by the groove or grooves 46 formed therein. Oil leaving the bearing surface of the thrust washer 45 flows downwardly around the exterior shaft bearing forming portion 32 of frame 31 and around the inside of the hollowed out portion of member 44 into the valley or trough 37. The valley or trough 37 is preferably inclined and drains the oil to the cavity 152 where it is

conducted into the hole 153 and directed by the passage 154 upon the compressor piston 54. Alternate pressure difference existing between the inside of the enclosing casing and the compressor cylinder causes oil at one time or another to be drawn toward the cylinder around the piston for lubricating same. The oil then drops into the body of liquid in the bottom of the unit where it is contained prior to again being separated from refrigerant and forced through the bearing surfaces of operating parts of the unit.

From the foregoing, it will be apparent that I have provided an improved sealed motor-compressor unit for a refrigerating system which has novel structural features for effecting quiet and efficient operation of the unit. The muffler device in the present structure substantially eliminates noise of refrigerant being compressed and discharged from the compressor and, by disposing same in the body of liquid in the bottom of the unit, the heat of compressed refrigerant flowing therethrough causes refrigerant to evaporate from the body of liquid to thus maintain the liquid richer in oil consistency. This feature, together with the fact that refrigerant is further separated from oil before the oil is circulated to operating parts of the unit, affords a system of lubrication with substantially pure oil which is important to the life of the unit. The provision of oiling the shaft bearing continuously from its bottom to its top, of oiling the bearing surface of the thrust washer and the compressor piston insures long life of the unit. The provision of grooves in the bearing surface of the thrust washer for facilitating lubrication thereof and for removing oil therefrom permits the escape of any refrigerant that may be carried into the shaft bearing along with the oil, and thus prevents this refrigerant from forming a lock which might otherwise block the flow of oil to the upper part of the shaft bearing and thrust washer bearing surface. The grooves in the bearing surface of the thrust washer also prevent the occurrence of intermittent differential in pressure within the shaft bearing to thereby eliminate noises which might otherwise occur by up and down movement of the shaft relative to the end of the shaft bearing.

While the form of embodiment of the invention as herein disclosed, constitutes a preferred form, it is to be understood that other forms might be adopted, all coming within the scope of the claims which follow.

What is claimed is as follows:

1. A sealed unit comprising, a casing having a motor and a compressor directly connected to said motor disposed therein and being resiliently supported therefrom, said casing being under compressor suction pressure, refrigerant conveying means having a connection with said compressor and a connection with said casing, said means including a device carried by said motor-compressor for receiving and muffling refrigerant discharged from said compressor, said means also including a pipe having an end secured to said device and having its other end secured to said casing for directing refrigerant discharged from said compressor to the exterior of said unit, said pipe being in the form of a coil and having a convolution thereof extending around said compressor to provide the pipe with a resilient portion intermediate its secured ends, and means abutting said compressor and applying force to said resilient intermediate convolution portion of the pipe coil at a plurality of widely spaced apart

points for preventing same from generating audible sounds.

2. A sealed unit comprising, a casing having a motor and a compressor directly connected to said motor disposed therein and being resiliently supported therefrom, said casing being under compressor suction pressure, refrigerant conveying means having a connection with said compressor and a connection with said casing, said means including a device carried by said motor-compressor for receiving and muffling refrigerant discharged from said compressor, said means also including a pipe having an end secured to said device and having its other end secured to said casing for directing refrigerant discharged from said compressor to the exterior of said unit, said pipe being in the form of a coil and having a convolution thereof extending around said compressor to provide the pipe with a resilient portion intermediate its secured ends, and means interposed between said compressor and said pipe coil permitting up and down movement of the coil relative to said casing, said means having its central portion abutting said compressor and having its ends straddling and applying force to said pipe coil convolution at a plurality of widely spaced apart points for preventing same from generating audible sounds.

3. A sealed motor-compressor unit including a casing under compressor suction pressure, a main frame within said casing supporting said motor-compressor therefrom, said main frame having a vertical bore forming an elongated bearing, a shaft within said bore, a motor stator carried by said frame and a motor rotor secured to the upper end of said shaft for rotating same, a plane surface on said frame perpendicular to the bore therein, a compressor secured to said plane surface of said main frame and depending therefrom, said compressor comprising a housing having a cylinder formed therein, a piston within said cylinder, said shaft having an offset portion depending below said frame and connected with said piston for reciprocating same within said cylinder during rotation of said shaft, the portion of said compressor housing secured to said plane surface of said frame being hollowed out to form with said plane surface walls of a plurality of closed chambers, said closed chambers being in communication with one another and with the inlet to said compressor, means communicating with the interior of said unit and with one of said chambers whereby refrigerant is directed first through one of said plurality of chambers and thence through another thereof to the inlet of said compressor for muffling the flow of refrigerant into the compressor cylinder, and a closed refrigerant conduit for conveying refrigerant discharged from said compressor exteriorly of said unit.

4. A sealed motor-compressor unit including a casing under compressor suction pressure, a main frame within said casing supporting said motor-compressor therefrom, said main frame having a vertical bore forming an elongated bearing, a shaft within said bore, a motor stator carried by said frame and a motor rotor secured to the upper end of said shaft for rotating same, a plane surface on said frame perpendicular to the bore therein, a compressor secured to said plane surface of said main frame and depending therefrom, said compressor comprising a housing having a cylinder formed therein with an axis perpendicular to the axis of said shaft, a piston within said cylinder, said shaft having a portion thereof de-

pending below said frame and connected to said piston for reciprocating same within said cylinder during rotation of said shaft, the portion of said compressor housing secured to said frame plane surface being hollowed out to form with said plane surface walls of horizontally spaced apart closed chambers, the one chamber disposed nearest to the axis of said shaft communicating with the other chamber and with the interior of said unit, the said other chamber communicating with the inlet to said compressor whereby refrigerant is directed through said one chamber and thence through said other chamber to the inlet of said compressor for muffing the flow of refrigerant into the compressor cylinder, and a closed refrigerant conduit for conveying refrigerant discharged from said compressor exteriorly of said unit.

5. A sealed unit comprising, a casing having a motor and a compressor directly connected to said motor disposed therein and being resiliently supported therefrom, said casing being under compressor suction pressure, refrigerant conveying means having a connection with said compressor and a connection with said casing, said means including a pipe for directing refrigerant discharged from said compressor to the exterior of said unit, said pipe being in the form of a coil and having a convolution thereof extending around said compressor to provide the pipe with a resilient portion intermediate the compressor and said casing, means interposed between said compressor and said pipe coil, and said last named means contacting said resilient intermediate convolution portion of the pipe coil at a plurality of spaced apart points and applying force thereto for preventing same from generating audible sounds.

6. A sealed unit comprising, a casing having a motor and a compressor directly connected to said motor disposed therein and being resiliently supported therefrom, said casing being under compressor suction pressure, refrigerant conveying means having a connection with said com-

pressor and a connection with said casing, said means including a pipe for directing refrigerant discharged from said compressor to the exterior of said unit, said pipe being in the form of a coil and having a convolution thereof extending around said compressor to provide the pipe with a resilient portion intermediate the compressor and said casing, means interposed between said compressor and said pipe coil, a spring member frictionally interposed between said compressor and said pipe coil, and said spring member contacting said resilient intermediate convolution portion of the pipe coil at a plurality of widely spaced apart points to apply force thereto for preventing same from generating audible sounds.

7. A sealed unit comprising, a casing having a motor and a compressor directly connected to said motor disposed therein and being resiliently supported therefrom, a refrigerant conveying conduit having a connection with said compressor and a connection with said casing, said conduit being of such length as to provide same with a flexible portion intermediate the compressor and said casing to permit limited movement of the compressor relative to the casing, and sound dampening means comprising a resilient member for applying force transversely to said flexible portion of said conduit.

8. A sealed unit comprising, a casing having a motor and a compressor directly connected to said motor disposed therein, a plurality of resilient means supporting the motor-compressor within said casing, each of said means including a coiled compression spring disposed in a vertical plane and supporting the weight of said motor-compressor, and each of said means also including a wire-like coil spring having its convolutions coiled around at least a part of a convolution of said first named spring whereby the axis of said last named spring substantially coincides with the axis of the wire forming said first named spring.
